UNITED STATES PATENT OFFICE

DWIGHT E. AUSTIN, OF LOS ANGELES, CALIFORNIA

DESIGN FOR A VEHICLE

Application filed August 20, 1930. Serial No. 36,720. Term of patent 14 years.

To all whom it may concern:

Be it known that I, DWIGHT E. AUSTIN, a citizen of the United States, residing at Los Angeles, in the county of Los Angeles and State of California, have invented a certain new, original, and ornamental Design for a Vehicle, of which the following is a specification, reference being had to the accompanying drawings, forming a part thereof, in which Figure 1 is a perspective view of the vehicle, with the view taken from one side and the forward end, and Fig. 2 is another perspective view thereof taken from the same side but showing a portion of the rear end.

I claim:

The ornamental design for a vehicle substantially as shown.

In testimony whereof, I have hereunto set my hand at Inglewood, California, this 15th day of August, 1930.

DWIGHT E. AUSTIN.
